SAFETY DEVICE FOR MULTIPLE SASH WINDOWS

Clarence Hobbs, Los Angeles, Calif., assignor to Universal Window Co., Berkeley, Calif., a corporation of California

Application May 20, 1952, Serial No. 288,778

2 Claims. (Cl. 20—42)

This invention relates to a safety device to be used in connection with automatically operating multiple sash windows.

By automatically operating multiple sash windows I refer to the outwardly swinging awning type sash of the kind disclosed in my assignee's patents issued to Esmond F. Wiley numbered Reissue 20,878, 2,158,714 and 2,232,297. All of the above mentioned patents, as well as others, disclose a window which comprises a plurality of sashes mounted for swinging movement in a single frame and embodying operating mechanism whereby all of the several sashes in any one frame may be opened and closed by manipulation of one sash which is usually the lower most sash of the group and is commonly referred to as the control sash. The patents also disclose means for rendering the connection between sashes ineffective whereby the single or control sash may be opened and closed independently of the others. In these prior patents the several sashes are described as being connected together by means of travel bars. However, the lower or control sash has a releasable connection with the travel bar generally referred to as a shoe or clutch. The construction of the shoe or clutch mechanism is such that upon manipulation of the control sash from a closed to an open position all of the connected sashes will be opened. Upon subsequent closing movement however of the control sash, the clutch has assumed a released position and the control sash or lower sash may be closed while the other sashes remain open. The construction of the clutch is such that upon the next opening movement of the control sash, reengagement is effected and when the control sash is again closed, the other sashes will be closed with it.

These windows have been found to present a hazard where they are used in a ground floor room in such a position that the lower or control sash projects outwardly when open into the path of the persons walking close to the exterior of the building. This is particularly true in schools where this type of window is frequently used and where the children's play area extends up to the building wall. Under these circumstances, if the lowermost sash, which is only a few feet from the ground, is left in its fully opened position, it presents a hazardous obstacle to children at play.

It is, therefore, the object of the present invention to provide a multiple sash window of the type described with means to prevent the lower or control sash from being left in its full open position without interfering with the normal operation of the window in which manipulation of the control sash serves to actuate the other sashes.

Further and more specific objects and advantages of the invention and a preferred structure for carrying it into practice are illustrated in the accompanying drawings and described in the following specification.

In the present disclosure I have, for purposes of illustration, shown the invention applied to the structure of

2

the Wiley patent, 2,158,714 hereinabove mentioned, but the application of the invention to other multiple sash windows will be apparent from the following description.

In the drawings:

Fig. 1 is a view in side elevation of the hardware employed on one side of a multiple sash window with the sashes illustrated in broken lines and showing the present invention applied thereto;

Fig. 2 is an enlarged detail in elevation of the clutch mechanism shown in Fig. 1;

Fig. 3 is an enlarged horizontal sectional view taken on the line III—III of Fig. 1 and also showing the window frame and parts associated therewith; and

Fig. 4 is an enlarged elevation of the lowermost portion of the hardware shown in Fig. 1 illustrating the position of a spring which forms a part of the present invention.

A general understanding of the operation of a multiple sash window of the kind to which the present invention is applied may be had from Fig. 1 in which three sashes are illustrated in broken lines at 10 as having been swung to their open positions. Each sash 10 is supported between a pair of hinge arms 11, one being shown as screwed to the side of each sash and as being pivoted at 12 to a shoe 13 carried for vertical sliding movement in a track 14 secured to the window frame by screws as shown in Fig. 3. A pair of links 15 is provided for each sash and these links are pivoted at one end to the window frame as indicated at 16 and at their opposite ends to the hinge arms as indicated at 17. When a sash is swung to its open position, it pivots about its connection with the link 15 and its associated shoe 13 slides downwardly in the track 14. Similarly upon closing movement of the sash the shoe 13 slides upwardly in the track 14. Travel bars 18 form connections between the shoes 13 through adjustable fittings shown at 19 to compel simultaneous movement of all the shoes 13 and therefore cause all of the sashes to open and close upon manipulation of a single sash.

In order to make the lowermost sash 10 an independently operable control sash, a clutch mechanism generally indicated at 21 and shown in detail in Fig. 2 connects the lowermost travel bar 18 with the lower sash. This clutch mechanism is fully described in the Wiley patent, 2,158,714, and includes a pair of pivoted tumblers 22 and 23 adapted to cooperate with the lowermost end of the travel bar 18 to effect engagement with and release therefrom in the sequence presently to be described, though the specific structure and manner of operation of the clutch will not be described herein as it is well known and does not form a part of the present invention.

The operation of the sashes shown in Fig. 1 starting with the clutch 21 in an engaged position and the sashes closed is as follows. Upon opening of the lowermost sash 10, the upper sashes are also swung to an open position. However, as the lowermost sash is closed, the clutch 21 is disengaged so that the uppermost sashes are left open. Upon the next opening of the lowermost sash to the angle at which the other sashes have been opened, the clutch reengages thus establishing a condition which will result in all of the sashes being closed when the lowermost sash is closed. This completes a cycle of operation so that all of the sashes may again be opened by opening movement of the control sash.

Now assuming that all sashes are swung to their open position, it is apparent from Fig. 1 that the lowermost sash 10, if only a few feet from the ground outside the building, presents a hazard to persons moving about in that area. The present invention, therefore, provides means for automatically returning the lowermost sash

to the position indicated in dotted lines where it is opened sufficiently to provide ventilation but does not project to a dangerous angle. This is accomplished in part by a spring shown at 25 in Figs. 1, 2 and 3, secured at its lower end to an anchor plate 26, best shown in Fig. 2 as fastened to one side of the clutch 21 by means of screws 27. The upper end of the spring 25 is anchored by a wood screw 28 shown in Fig. 3 as threaded into the wooden frame member which is illustrated at 29. The frame member is rabbeted for reception of the track 14 and associated hardware, as is also a stop member 30 which serves as an abutment for the sash 10 and conceals the hardware. The rabbeting in the frame 29 and stop member 30 is sufficiently extensive to include the spring 25. As the spring is stretched or tensioned upon opening of the lower sash, it will draw the clutch member 21 upwardly in the track 14 and thus swing the lower sash toward its closed position as soon as it has been released. The spring 25 is tensioned to close the lower sash to approximately the position illustrated in dotted lines in Fig. 1. In order to prevent further closing of the lower sash as by gravity or wind pressure, a second spring shown at 32 in Figs. 1 and 4 is associated with the track 14 and the lower part of the lowermost link 15. Spring 32 is a torsion spring held in place by an anchor screw 33 about which it is twisted. One end of the spring engages beneath the inturned edge of the track 14 and the opposite end is bent over the upper edge of the link 15 as illustrated at 34. This spring is tensioned to prevent closing of the lower sash beyond the dotted line position of Fig. 1 but this tension is overcome when the lower sash is grasped manually and drawn to its closed position. Thus the springs 25 and 32 tend to retain the sash in its safe position though their tendency to do so may be overcome by manual manipulation of the sash to effect the cyclic op-

5

eration hereinabove described. The invention is illustrated herein as applied to the hardware on one side of the window and though one set of springs will perform the desired function, it is preferred that the same arrangement be employed on both sides.

I claim:

1. In a multiple sash awning type window wherein one sash controls the movement of the other sashes and is releasable therefrom for independent swinging movement, resilient means associated with said one sash automatically to swing it toward its closed position when it is released from its controlling relationship with the other sashes and separate resilient means tending to prevent complete closing of said one sash.

10

2. In a multiple sash window of the awning type wherein all sashes are supported by hinge arms fixed to the sashes and slideable vertically in the window frame upon opening and closing of the sashes and wherein all sashes have links pivoted to them and to the frame, means connecting the slideable hinge arms to compel the sashes to swing simultaneously, a releasable clutch in one such connecting means to permit independent operation of one sash, a spring associated with said clutch to urge said sash toward its closed position when the clutch is released, and a second spring acting between the frame and a pivoted link of said sash to urge it away from its fully closed position.
